HAT CLAMP

Henry M. Pernini, Chicago, and Nano F. Contardi, Highland Park, Ill.

Application August 7, 1946, Serial No. 688,938.

12 Claims. (Cl. 223—25)

1

The present invention relates to hat clamps for use in the process of blocking hats and more particularly to the type of clamp utilizing a circular expandable strip to engage the sweatband of a hat.

It is an object of the invention to provide an improved form of clamp having a compressible handgrip in which the force of outward expansion varies with the pressure exerted on the handgrip and in which means are provided which act automatically as an incident to the release of manual pressure to maintain the clamp in its expanded condition.

It is another object of the invention to provide an improved hat clamp having a centrally mounted handgrip which is effective both to apply clamping pressure and to enable single handed positioning thereof and which further includes means for enabling single handed release and withdrawal.

It is a further object of the invention to produce a hat clamp which enables the maintenance of large clamping forces as long as desired but which at the same time is simple and straightforward in construction and operation and inexpensive to manufacture.

It is a still further object to produce a hat clamp for use with a forming flange which insures that a cleaned and blocked hat is accurately sized.

In one of its aspects it is an object of the invention to provide an expandable hat clamp which is automatically locking in an infinitely adjustable condition of expansion.

Further objects and advantages of the invention will become apparent as the following description proceeds, taken in connection with the accompanying drawings in which:

Figure 1 is a plan view of a preferred form of hat clamp embodying the invention.

Fig. 2 is a sectional view reduced in scale showing the hat clamp of Fig. 1 in its inserted position adjacent the sweatband of a hat.

Fig. 3 is an enlarged sectional view taken along line 3—3 of Fig. 1.

Fig. 4 is an enlarged sectional view taken along line 4—4 of Fig. 1.

Fig. 5 is a plan view of another form of hat clamp embodying the invention in somewhat reduced scale as compared to Fig. 1.

Fig. 6 is an enlarged sectional view taken along line 6—6 of Fig. 5.

While the invention is susceptible of various modifications and alternative constructions, we have shown in the drawing and will herein de-

2

scribe in detail the preferred embodiment; but it is to be understood that we do not thereby intend to limit the invention to the specific form disclosed but intend to cover all modifications and alternative constructions falling within the spirit and scope of the invention as expressed in the appended claims.

Referring now to the drawing it will be seen in Fig. 1 that the clamp indicated generally at 10 consists of two portions, the first being a flexible strip 12, which is bent into circular or elliptical form and an expanding and locking portion 14 which is mounted centrally therein. In use the clamp is inserted into a hat 16 positioned in a flanging ring 18 as shown in Fig. 2. By means of the expanding and locking portion of the device the strip is forced radially outward and into forceful engagement with the sweatband of the hat. This serves both to hold the hat securely for the steaming and flanging operation and to smooth the surface of the sweatband and form it to the proper size.

As to the details of our improved construction disclosed in Fig. 1, it will be seen that the strip 12 is formed of a rolled piece of flat stock having an outer overlapping end 20 and an inner overlapping end 22 both of which are normally caused to lie in close sliding engagement with the intermediate portion of the strip. Fastened near the ends of the strip 12 are brackets 24 and 26 pivotally engaging the divergent movable ends of a generally V-shaped handgrip 28. The handgrip includes two legs 30 and 32 respectively which are pivoted to each other by means of a pivot pin 34 and likewise pivoted to the brackets 24 and 26 by pivot pins 36 and 38 respectively. It will be understood, however, that in place of the pivot pins illustrated, any mechanical hinging or pivoting means may be used which will allow a substantially equivalent movement.

The legs of the handgrip, which may be formed by a casting process, preferably are scalloped out to provide a gripping recess 40 for the thumb, and recesses 42 for the fingers of the operator, such recesses overcoming any tendency for the operator's hand to slide along the tapered surface as gripping pressure is applied. It will be noted that the legs of the handgrip are quite long, occupying nearly all the available diametral space and providing a maximum of leverage for expanding the strip. In addition to providing a means for expanding the strip it will be apparent that the handgrip may also be employed to allow single handed placement and adjustment of the clamp within the hat.

In the preferred embodiment illustrated, means are provided for keeping the ends 20, 22 of the strip in close sliding contact with the intermediate portion thereof so that the force exerted on the ends of the strip by the handgrip is tangential in nature. An enlarged detail view of the structure providing a slide and associated with the bracket 26 is shown in Fig. 3. Here it will be observed that the end 22 of the strip is fixed to the bracket 26 by screws 44 which preferably have flat tapered heads for riding in a longitudinal slot 46 extending along the intermediate portion of the strip 12. The portions of the strip adjacent the edges of the slot are preferably tapered to register with the taper of the screwhead and thereby to enable the screwhead to be completely below the level of the outwardly presented surface of the strip. This construction, although keeping the end 22 of the strip in intimate sliding engagement with the strip body, completely avoids the danger of marring the sweatband material during the process of adjustment and applying clamping pressure.

A somewhat similar arrangement is used at the overlapping end 20 attached to the leg 39 (Fig. 4). Here, however, the bracket 24 is solidly connected to the outer one of the two sliding portions of the strip by flatheaded screws 48, and a longitudinal slot 50 is formed in the body of the strip to provide access between the end of the strip 20 and the associated leg of the handgrip. As an additional means for insuring alignment of the relatively movable portions of the strip, bent-over registering edges 52 are used. Such edges are formed on the edge of the clamp which are designed, in use, to lie above the level of the sweatband so as not to groove it. Then, too, the edges 52 serve as a limit stop for insertion and protect the stitching at the edge of the band from the effects of steam.

In accordance with one aspect of the invention means are provided for biasing the legs 30 and 32 of the handgrip away from one another, the latter position corresponding to a condition of minimum diameter of the strip and enabling ready insertion of the clamp within even the smallest sizes of hats. In the present embodiment the latter is accomplished by constructing the strip 12 of springy material and prestressing it so that it tends normally to assume a minimum diameter. Fig. 1 shows the clamp in the latter condition.

It is apparent from the foregoing that manual pressure on the grip 28 will cause the strip to expand outwardly. To hold the strip in its position of maximum expansion and to prevent retrograde movement between the legs of the grip while the hat is being treated, we provide, in the preferred embodiment, a friction ratchet. The latter may include an arcuate rod or bar 54 which is circular in section and attached near the end of leg 30 by means of a pivot pin 56. The rod is freely slidable with respect to the remaining leg 32 of the handgrip and is lockingly engaged by means of a locking tab 58. The latter is pivoted for movement in the plane of the bar 54 since it is mounted on a pivot pin 60 on the central portion of the leg 32. At its outer end the locking tab has an aperture through which the rod 54 is passed and which is just slightly larger than the outer diameter of the rod. The locking tab 58, or at least the portion thereof surrounding the aperture, is preferably constructed of metal of extreme hardness and the edges of the aperture are preferably sharp so that under "locked" 75

conditions such edges may bite into or seize the relatively softer arcuate rod 54. Means are included in the ratchet for biasing the locking tab 58 outwardly from the leg 32 so that the sharp edges of the aperture 62 are at all times in a position to produce a locking engagement. In the present instance a simple compression coil spring 64 bridging the leg 32 and the locking tab is used.

- 10 While the judgment of the operator as to the pressure to be applied enables the above described clamp to be effectively used, nevertheless it will be noted that additional means are provided for insuring that the sweatband is expanded to exactly the proper size. In the present embodiment this is accomplished by indicia 70 which are stamped or otherwise applied to the arcuate bar 54. Such indicia may read directly in terms of the hat size desired, generally increments of eighths of an integral hat size. Any desired type of cooperating pointer may be used to cooperate with the indicating marks; however, we prefer to use the right-hand edge 71 of the leg 32 for this purpose. This means for indicating the exact size to which a sweatband has been expanded is particularly advantageous since heretofore it has been necessary to depend upon the internal diameter of a selected forming flange for performing this function. 20 Thus if a given hat happened to have a particularly thick felt body, hat band, and sweatband, the blocked size was likely to be too small. Conversely, if the felt and associated bands were thinner than average, the hat returned to the 30 customer after blocking would, in all probability, be too large. In our improved construction, however, the size of the blocked hat is determined directly and with absolute accuracy as an incident to clamping the hat within the flange. 35 40 The concept of direct rather than indirect determination of a proper hat size in addition to greatly speeding up the blocking process and enabling it to be accomplished by an unskilled operator has the advantage that the customer is 45 invariably satisfied with the work returned to him.

Although the operation of the device will be apparent from the foregoing description, it will be helpful to summarize it briefly. Initially the 50 strip 12 will be in a condition of minimum diameter due to the prestressing or coiling of the strip in manufacture, such condition corresponding to maximum separation of the legs 30, 32 comprising the grip. The handgrip is grasped lightly 55 and the clamp inserted into its position within the sweatband. Upon applying a greater gripping force, the ends of the strip 12 are forced toward one another and the band expands outwardly, flexibly adjusting itself to the oval shape 60 of the hat and flanging ring. The gripping pressure is increased until the desired size is indicated by the indicia 70 or alternatively until the operator can "feel" that proper clamping pressure is being applied, whereupon manual pressure is released. Any tendency toward retrograde movement of the arcuate rod 54 results in further cocking of the locking tab 58 and consequent seizing of the rod by the sharpened edges 65 of the aperture 62.

70 In order to remove the clamp from the hat after the flanging and steaming have been completed, it is merely necessary for the operator to again apply gripping pressure which disengages the ratchet. While such pressure is being applied, the operator need only press the tip of

one of his gripping fingers against the locking tab 53 in a direction to compress the coil spring 64. Subsequent release of gripping pressure will then cause the clamp to automatically assume a condition of minimum diameter and the clamp may be removed from the hat.

Alternate construction

Although the preferred form of the hat clamp discussed immediately above has been found to be extremely well suited for its intended use, the modification shown in Figs. 5 and 6 possesses the same primary advantages while having the further advantage of being simpler and cheaper to manufacture. Here a strip of springy material 12a is used which, as in the previous embodiment, is preferably prestressed so that it is normally of a minimum diameter producing maximum overlap of the ends 20a and 22a. The handgrip includes legs 30a and 32a which are divergently arranged and which are preferably formed of light gauge metallic channel.

The legs 30a, 32a are mutually pinned at their inner ends by a pivot pin 34a and are further pivoted at their outer ends to brackets 24a and 26a by pins 36a and 38a respectively. The brackets are joined to the overlapping ends 20a and 22a respectively of the strip, the cross section of bracket 26a being shown in the sectional view of Fig. 6. There it will be seen that the bracket consists merely of a pair of integral ears which are cut from the strip itself and bent inwardly along a nonsevered edge to present a mounting which allows passage of the pin 38a. It will be understood that the remaining bracket 26a may be formed in the same manner from the overlapping portion 20a of the strip. In the latter case, however, a longitudinal groove must be cut in the intermediate portion of the strip 12a for passage of the bracket 24a into the circular confines of the strip. Although the latter detail has not been specifically illustrated, the manner of accomplishing such construction will be obvious since completely analogous to that shown in Fig. 4 in connection with the previous embodiment.

In order to keep the legs of the grip in a locked condition after they are compressed, a ratchet arrangement is used consisting of an arcuate bar 54a having teeth oriented to the left as viewed in Fig. 5. The bar is pivoted to one of the legs 30a by a pin 56a while the opposite or toothed end is received in an aperture 57 in the remaining leg. The lower edge of the aperture is preferably sharpened and constructed of hard material for cooperation with the ratchet teeth. A tension spring 64a, which in the present embodiment is shown anchored to the leg 30a, normally maintains the ratchet teeth in engagement. The ratchet may be released, however, by one of the fingers of the gripping hand of the operator merely by applying upward pressure to a small knob or projection 59 on the arcuate bar.

The size to which the band 12a is expanded is indicated accurately by indicia 70a on the arcuate rod 54a, the selected size being aligned with any desired indicating pointer such as the right-hand edge 11a of the leg 32a.

The operation of this embodiment will not be discussed since it is completely analogous to that already discussed. Suffice it to say that retrograde movement is prevented by means of the toothed ratchet and that in this embodiment the adjustment is limited to finite steps depending upon the spacing of the teeth in the ratchet.

Although the use of the clamp has been described in connection with the clamping of a hat in a flanging ring, it will be obvious that the clamp is similarly well suited for use as a hat stretcher. If it is desired to stretch a hat to size it is merely necessary to insert the clamp and apply gripping pressure to an extent dependent upon the type of headgear and the amount of enlargement desired. Due to the improved locking means, the exact amount of expansion may be maintained for extended periods of time.

With regard to the materials of construction, we prefer to use stainless steel. It will be apparent, however, that other metals or alloys may be used which are corrosion resistant and which further have the required strength and elasticity.

We claim as our invention:

1. A clamp for use in the blocking of hats comprising a circular sweatband-engaging strip having inner and outer overlapping ends, a generally V-shaped grip having legs pivoted for movement toward one another and lying within said circular strip, means connecting the diverging ends of said legs to said overlapping ends respectively of said strip so that manual inward pressure on said legs causes an increase in the average diameter of said circular strip, and locking means to maintain said strip in its expanded condition as an incident to the release of manual pressure therefrom.

2. A clamp for use in the blocking of hats comprising a generally circular sweatband-engaging strip having overlapping ends, a grip having legs pivoted for movement toward one another and lying within said circular strip, means connecting the movable ends of said legs to said overlapping ends respectively of said strip so that manual gripping pressure on said legs causes an increase in the average diameter of said circular strip, a locking bar pivoted to one of the legs and slideable transversely with respect to the other, and means acting on the slideable end of said locking bar for maintaining said legs in the position of closest approach upon release of manual pressure therefrom.

3. A clamp for use in the blocking of hats comprising a generally circular sweatband-engaging strip having flatly overlapping ends, a handgrip lying within the confines of said strip and having legs pivoted for movement toward one another, means connecting the movable ends of said legs to said overlapping ends respectively of said strip so that manual gripping pressure thereon is accompanied by an increase in the peripheral length of said circular strip, an arcuate bar pivoted on one of said legs and slidably received in the other near the movable ends respectively of said legs, ratchet means associated with the slideable end of said arcuate bar causing locking of the legs against separating movement upon the release of manual pressure therefrom, and means manipulable by the fingers of the hand while grasping said grip for disengaging said ratchet means.

4. A clamp for use in the blocking of hats comprising a generally circular sweatband-engaging strip having flatly overlapping ends, a handgrip lying within the confines of said strip and having legs pivoted for movement toward one another, means connecting the movable ends of said legs to said overlapping ends respectively of said strip so that manual gripping pressure thereon is accompanied by an increase in the peripheral length of said circular strip, an arcuate bar piv-

oted on one of said legs and slidably received in the other near the movable ends respectively of said legs, ratchet means associated with the slideable end of said arcuate bar causing locking of the legs against separating movement upon the release of manual pressure therefrom, and means for manually disengaging said ratchet means, said strip being prestressed to assume a condition of minimum average diameter and maximum divergence of said legs upon release of said ratchet means.

5. A clamp for use in the blocking of hats comprising a generally circular strip having inner and outer overlapping ends, a handgrip including two mutually pivoted and diverging legs lying within the circular confines of said strip, means for attaching the ends of said legs respectively to the overlapping ends of said strip so that gripping of said legs causes radial expansion of said strip, a rod bridging the movable ends of said legs, said rod being in engagement with one of said legs and slideable with respect to the other, and friction ratchet means associated with said other leg to engage said bar and prevent retrograde movement thereof upon release of manual pressure from said grip.

6. A hat clamp comprising a generally circular strip having flatly overlapping ends, a handgrip including two legs pivoted to one another for movement in the plane of said circular strip, means for attaching the ends of said legs to the overlapping ends of said strip so that gripping of said legs causes radial expansion of said strip, a rod bridging the movable ends of said legs, said rod being in engagement with one of said legs and slideable with respect to the other, and friction ratchet means on said other leg including a locking tab pivoted thereon for movement in the plane of said rod and having an aperture therein for the free admission of said rod, said tab being arranged so that the passage of said rod therethrough upon application of gripping force may readily occur but so that any retrograde movement of said rod causes cocking of said tab and consequent locking engagement between the edges of said aperture and said rod.

7. A hat clamp comprising a strip bent into circular form and having overlapping ends, an operating handgrip lying inside said strip and having opposed legs mounted for movement toward one another, means for respectively attaching the ends of said legs to the ends of said strip so that grasping of said handgrip causes radial expansion of said strip, a rod bridging the movable ends of said legs, means mounting said rod in engagement with one of said legs but slideable with respect to the other, and friction ratchet means on said other leg including a locking tab pivoted thereon for movement in the plane of said rod and having an aperture therein to freely receive said rod, said tab being movable into a cocked position with respect to said rod in which any tendency toward retrograde movement causes the opposed edges of said aperture to seize said rod, and biasing means for maintaining said tab in its cocked position.

8. A hat clamp comprising a generally circular strip having overlapping ends, a generally V-shaped handgrip lying within the confines of said strip, said handgrip including two legs mutually pivoted at one end and having their other ends attached to the ends respectively of said strip so that manual pressure on said grip expands said circular strip radially outward, a

toothed ratchet bar pivoted to one of said legs and bridging the latter, and means on the other of said legs for engaging the toothed portion of said bar, the teeth of said ratchet bar being oriented in a direction to prevent retrograde movement of said bar upon release of manual pressure from said grip.

9. A hat clamp comprising a generally circular strip having inner and outer overlapping ends, a handgrip lying within said strip, said handgrip including two legs mutually pivoted at one end and having their other ends attached to the ends of said strip respectively so that manual pressure on said grip expands said strip outwardly, means including a toothed ratchet bridging said legs for preventing retrograde movement of said legs upon release of manual pressure on said grip, resilient means for maintaining said ratchet in engagement, and means manipulable with the fingers of the gripping hand of an operator for releasing said ratchet.

10. A hat clamp comprising a circular sweatband-engaging strip having flatly overlapping ends, a handgrip lying within said strip and having legs pivoted for movement toward one another, means connecting the movable ends of said legs to the overlapping ends respectively of said strip so that manual gripping pressure causes said strip to expand outwardly, said strip being prestressed so that it normally assumes a position of minimum diameter, and means maintaining at least one end of the strip in intimate sliding engagement with the flatly adjacent intermediate portion of said strip.

11. A clamp for use in cooperation with a forming flange in the blocking of hats comprising a generally circular sweatband-engaging strip having inner and outer overlapping ends, means including a compressible handgrip for increasing the average diameter of said strip upon application of increased gripping pressure, and indicating means operating as an incident to compressing said handgrip for indicating the hat size to which the strip is expanded.

12. A clamp for use with a forming flange in the blocking of hats comprising a generally circular sweatband-engaging strip having overlapping ends, a generally V-shaped grip having legs pivoted for movement toward one another and lying within said circular strip, means connecting the movable ends of said legs to said overlapping ends respectively of said strip so that manual gripping pressure on said legs causes an increase in the average diameter of said circular strip, a locking bar pivoted to one of said legs and slideable transversely with respect to the other, means acting on the slideable end of said locking bar for maintaining said strip in a condition of selected average diameter, and means including indicia on said locking bar for indicating the selected average diameter of said strip directly in terms of hat size.
